UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

TYPE-WRITING MACHINE.

1,288,720.

Specification of Letters Patent. Patented Dec. 24, 1918.

Original application filed April 28, 1917, Serial No. 165,055. Divided and this application filed July 1, 1918. Serial No. 242,734.

To all whom it may concern:

Be it known that I, JESSE A. B. SMITH, a citizen of the United States, residing in Stamford, in the county of Fairfield and 5 State of Connecticut, have invented certain new and useful Improvements in Type-Writing Machines, of which the following is a specification.

This invention relates to typewriting machines, especially to machines which are intended to be used for writing on webs of paper, and have a revoluble platen and a traveling carriage.

The invention is herein disclosed as applying to an Underwood typewriting machine, modified somewhat along the lines of the patent to Wernery & Smith, 1,132,055. The machines disclosed in said patent are capable of writing upon what is known as a 20 fan-fold web, which is so folded as to make several thicknesses of work-sheets which afterward can be separated.

Such a fan-fold web has the great advantage that headings, etc., printed thereon, are 25 positively held in alinement with each other upon the several plies even when feeding around the platen, because each web or ply is bound to the two adjacent webs by the integral edges at the fold, and these prevent 30 either ply of the fan-fold sheet from feeding faster than the others.

The present invention is a division of my application, Serial No. 165,055, filed April 28, 1917, and includes devices which are 35 adapted to retain many of the advantages of said patent, and at the same time enable separate webs or plies to be used with facility, thus permitting one web to be of one color or quality of paper, while the other 40 webs may be of different qualities or colors.

In the form of the invention herein disclosed, the carriage of the typewriter is in many respects like that in the patent referred to, and includes a carbon paper carriage which is adapted to be moved forwardly and backwardly along the usual typewriter carriage. The webs of paper, owing to their weight, are usually mounted upon stationary supports, so that the typewriter carriage is relieved of the strain of 45 driving them. The rolls, which deliver the webs to the typewriter carriage, are, according to the present improvements, placed so

that before reaching the typewriter carriage, the webs are free of tension or are unsupported for quite a distance, thus allowing the typewriter carriage to travel almost unimpeded by the webs, because the space over which the webs are free of tension enables the webs to twist freely and idly in that space. Instead of being actually unsupported, the webs may lie for a part or all of the distance upon a flat table, which permits them to slide or swerve sidewise at will.

Owing to the fact that the paper forming 65 the webs has some thickness, and that this thickness at the platen is materially increased by interleaved carbon papers, the outside web normally would tend to travel considerably faster around the platen than 70 the inside web, with the result that if the forms printed on the different webs register when the leading edges of the webs are first inserted into the typewriter, they very soon cease to register because the outside web 75 travels faster than the inside web.

The invention may also include a connection to the carbon paper carriage, such that when pushed rearwardly, the carriage will unwind practically the full length of a form 80 from the webs, so that the subsequent line-spacing operation in filling out the forms, will not throw upon the line-space lever the load of unwinding the webs. This also has the advantage of producing some slack in 85 the webs which serves to diminish the side twisting of the webs which ensues from the travel of the typewriter carriage.

Other features and advantages will hereinafter appear.

In the accompanying drawings,

Figure 1 is a perspective view, largely broken away, showing the invention as applied to the machine of the aforesaid patent.

Fig. 2 is a sectional side view of the same, 95 with the parts set for beginning to fill out a fresh form.

Fig. 3 is a sectional side view, showing the webs stretched out straight, and the carbon paper carriage clamp released, just at the 100 moment of starting to push the carbon paper rearwardly, preparatory to bringing a new form to the printing point.

Fig. 4 is a view similar to Fig. 3, but shows the carbon paper carriage clamp released at the end of its rearward movement.

In the Underwood typewriting machine, types 1 at the outer ends of type-bars 2 strike against the front side of a rotatable platen 3 in a carriage 4. The platen 3 is 5 rotated by means of a knob 5, mounted on a stub axle 6; or by the line-space lever 7, which is adapted to drive rearwardly a slide 8 effective on the line-space detent wheel 9. The platen is mounted in a swing frame 10, 10 which is journaled on a front axle 11, in such a way that as the swing frame 10 is thrown upwardly and forwardly, the platen swings therewith, but is constantly kept engaged with the line-space mechanism be- 15 cause a pinion 12 fast to the end of the platen axle, remains in mesh with a pinion 13 fast on the shaft 11, and the pinion 13 is also in mesh with a pinion 14 fast to the stub axle 6. When the swing frame 10 is 20 swung up, the platen occupies the position seen in Fig. 3, in which position webs 15, 16 and 17 may be drawn practically straight from the rear of the machine under the platen to have their leading ends gaged by 25 an adjustable outer end gage 18.

After being thus drawn forward and gaged, the webs are usually cut off. This is done after the platen 3 is swung back to its normal position, there being provided for 30 this purpose a knife 19, adjacent the front of the machine. The usual front and rear feed rolls 20 and 21 hold the webs 15, 16 and 17 against the platen, during the severing operation, while the platen is latched in its 35 downward normal position by the usual latch 22, which is swung forward by a spring 23, so that it catches over a pin 24 on the handle 25, which is provided for swinging the swing frame 10 upward and 40 forward.

As the webs 15, 16 and 17 are fed forward for the purpose of writing on them, they draw with them interleaved carbon sheets 26 and 27, which are clipped to the 45 usual cross-bars 28 projecting from the opposite sides of a carbon carriage 29, common in this type of machine. The carbon paper carriage 29 runs on rolls 30, which roll on rails 31 fast to the typewriter carriage, said 50 rails being united by a cross-bar 32 at their rear ends, thus forming a frame which includes a wheel 33, traveling on a rear rail 34. At the front end the rails are fast to brackets 35 on the typewriter carriage adjacent the usual rear carriage rail 36. When 55 the webs 15, 16 and 17 are stretched out flat in the manner shown in Fig. 3, the carbon paper carriage 29 is usually pushed rearwardly by handle 37, so as to shift the carbon paper sheets 26 and 27 back to the 60 position seen in Fig. 4, in which position, the carbon paper sheets are clear of the knife 19, with the result that the carbon paper sheets remain intact while the webs are being later 65 torn off.

In order to properly align the webs, there are provided on the swing frame 10 adjustable edge gages 38, formed as the turned-up edges of plates 39, which lie on the table 40. Besides the edge gages 38, there are also 70 provided edge gages 41 adjustably mounted on the carbon paper carriage 29, these latter edge gages serving to guide the webs straight as they approach the platen 3.

The webs as herein shown are drawn from 75 three spools 42, 43 and 44, which are journaled on spindles in a suitable fixed frame 45. As herein illustrated, these spools are beneath the typewriting machine and may be conveniently placed near the floor, under 80 whatever table the typewriting machine is mounted on for the time being. From the spools 42, 43 and 44, the webs are led past guides 46 from which they extend in a straight clear reach to a second set of guides 85 47. The reach from 46 to 47 may be equal to or greater than the travel of the carbon paper carriage 29, for reasons which will presently appear.

From the guides 47, the webs rise and turn 90 forwardly over the rod or bar 32, which, therefore, may, if desired, be several feet vertically from the guide 47, thus making any twisting of the webs, between 47 and 32 95 (due to travel of the typewriter carriage), of negligible effect on the webs from the rod 32 forward to the platen 3.

In connection with the rolls 42, 43, 44, there is provided a web-advancing clamp 72, as part of the lower carriage 73, which is 100 provided with rolls 74 to run on rails 75 extending rearwardly from the support 45. The clamp 72 may include jaws 76 and 77 and is preferably in duplicate, so that there is such a clamp 72 near each margin of the 105 webs 15, 16 and 17. To operate these clamps together, they are mounted on a transverse shaft 78, which is provided with a rock arm 79 having a pin 80 working in a cam slot 81 in a plate 82. This plate is preferably connected to be operated by a finger-piece 57 by means of a horizontal link 83 extending from a lower extension 84 of said finger-piece, said link 83 operating a rock arm 85 fast to the end of the shaft 86 at one side of the typewriter carriage. This rock arm operates the cam plate 82 by means of the rock shaft 86, said rock shaft having also fast thereto a second rock arm 87, which is joined by a link 88 to a rock arm 89 splined to a shaft 90 adjacent the shaft 94. The shaft 90 is journaled on brackets 91 forming part of the carriage 73, and operates the cam plate 82 by means of arms 92 and 93 on the shafts 90 and 94, respectively, said arms being joined by a link 95.

It will be seen that the finger-piece 57 is adjacent the handle 37 and pivoted thereon at 58, so that the hand of the typist, in adjusting the carbon paper by the handle 37, is 130

enabled to readily adjust the finger-piece 57 by motion of the handle at the same time.

The carriage 73 has been described as running on fixed rails 75, while the carbon paper carriage 29 runs on the rails 31, which form part of the typewriter carriage. In order to enable the link 88, which connects the finger-piece and clamp 72, to remain vertical despite the feeding of the typewriter carriage 10 sidewise past the lower carriage 73, the splined arm 89 is slid along its shaft 90 by means of a stiff vertical bar 96 projecting downward from the carbon paper carriage and having at its lower end a fork 97 15 which embraces the rock arm 89, thus causing said rock arm to slide along its shaft with the travel of the typewriter carriage.

When the carbon paper carriage is pushed back, the clamp 72 will be seizing the lower 20 reaches of the webs 15, 16 and 17 between the supports 46 and 47, thus unwinding each web 15, 16 and 17 from its spools 42, 43 and 44 an amount precisely equal to the amount that the carbon carriage is pushed backward. This produces a bight 98 in the webs 25 between the support 47 and the rod 32. When the carbon paper carriage is pushed all the way back, the stop 69 causes the clamp 72 to release. Since the clamp 72 is released, it follows that during the subsequent 30 forward feeding of the webs 15, 16 and 17 with the carbon sheets 26 and 27 around the platen, the lower reaches of the webs are entirely free of the lower clamp 72, and 35 hence the forward movement of the carbon paper carriage with the carriage 73 does not result in retracting any of the bight 98 over the support 47, that is, to the right at Fig. 2. During such forward movement of the carbon carriage, the bight or slack at 98 is partly or wholly taken up, such bight being replaced by the next rearward travel of the lower carriage 73.

When the platen is in the Fig. 3 position, 45 the clamps 72 will seize, if the typist pushes back the carbon paper carriage at this time, with the finger-piece 57 in the Fig. 3 position. Thus a bight 98 is formed every time the carbon paper carriage 29 is pushed rearwardly, and this bight is gradually taken up by the line-spacing or other feeding of the webs around the platen. It will be usually found advantageous to adjust the webs at the beginning in such a way that there is an 55 initial extra bight between 47 and 32, this bight, of course, being much greater when the carbon paper carriage carries the lower carriage 73 rearwardly than it is at other times.

When the finger-piece 57 is pulled forward 60 to the Fig. 3 position, a bell-crank 62 may be actuated by means of a link 59 extending from said finger-piece 57 to swing an arm 66 of said bell-crank and permit a latch 34 to be drawn by a spring 65 under the arm 66 65 of said bell-crank, thus latching the finger-

piece in its forward position and therefore holding the clamp 72 locked in its effective position.

The clamp 72 may be released at the end of the rearward movement of the carbon carriage 29. This may be done by a tail 67 of the latch 64, projecting downwardly below a pivot 68 thereof, which strikes against a stop 69 secured on the left-hand rail 31, thus causing the latch 64 to free itself from the bell-crank 62, thereby permitting a spring 70, coiled around the shaft 71, to rock said shaft, and, by means of the mechanisms connecting said shaft with the clamp 72, cause said clamp to become ineffective. 80 The stop 69 which arrests the carbon paper carriage 29 may be adjustable, and fastened at any point of the rail 31 to suit the work in hand. For this purpose, it is held to said rail by a thumb-screw 71.

There may be provided a table 99, which extends rearwardly from the support 47, and is preferably either entirely without sides, except immediately adjacent to support 47, or has such low sides that the bight 98 can 90 slip over the sides of the table. The table may be formed from two plates of sheet-metal, each slideable on, and embracing a lower rod 100, and having a sleeve 101 sliding on an upper rod 102, the rods 100 and 95 102 forming the support 47. The rear end of the plates forming the table 99 may be bent downward, as seen in Fig. 3, so that when the web is drawn rearwardly by the clamp 72, it will form a bight, slack or supply, which at first will lie on the table 99, but which will be gradually taken up in the line-spacing operation during the typewriting or filling in of the various blanks on the web work-sheet. The plates forming the table 99 100 may have their edges turned up at 103 to 105 form ears on which the sleeves 101 are mounted. These ears form edge guides for the webs 15, 16 and 17, but the ears are preferably cut off close to the rod 100, so that 110 the edge guides formed thereby are extremely short, thus allowing the webs to slip sidewise or twist on the table 99.

In order to keep the weight of the webs 15, 16 and 17, between the supports 46 and 115 47, from drawing the bight of the web off the table 99, thereby allowing the webs to sag down between said supports 46 and 47, the jaws 77 of each clamp 72 may be elevated above the plate 104 which forms the top of 120 the carriage 73, and the jaws 77 may be cut off at the sides of the clamps 72 near the center, to make room for a fixed plate 105 lying between the jaws 77 and extending beneath the webs 15, 16 and 17 to support them 125 throughout their length between the supports 46 and 47. The plate 105 forms a table having an extension 106, which embraces the rod 100, and a second extension which embraces a rod 107, forming the lower 130

rod of the support 46. Thus it will be seen that the webs 15, 16 and 17 are supported horizontally throughout their length from the support 46 to the support 47, except at 5 their margins which extend beyond the plate 105, and therefore can be gripped by the clamp 72. The webs do not sag between the rails 31 because the usual supporting rods shown in the patent to Jesse A. B. Smith, 10 No. 1,177,546, not seen herein, support the web where it does not rest on the carriage 29. On the machine herein shown, the spools 42, 43 and 44 are positioned vertically below the center of the typewriting machine, 15 and consequently below the center of the travel of the typewriter carriage. With the rolls in this position on the machine, the typist may draw the webs 15, 16 and 17 straight onto the platen without any twisting whatsoever if the typewriter carriage is 20 positioned at the center of its travel. The typist, however, will often draw on the webs with the typewriter carriage positioned elsewhere than the center, thus tending possibly to some extent to twist the webs. In order 25 to positively align the webs at will, both as to twisting and to cause the forms printed on different webs to register with each other, means may be provided whereby the typist 30 can accurately re-register the webs at frequent intervals, independently of any other devices, thus avoiding the necessity of re-adjusting the other devices, especially if a narrow web is used temporarily. For this purpose, the webs are shown herein as provided 35 with perforations at identically corresponding points, 108, and the end gage 18 is provided with a tapered pin 109 of the same size as the perforations 108, so that the typist can 40 draw the webs out horizontally as shown in Fig. 4, and align and re-align the corresponding printed forms on the various plies whenever required, this being accomplished by fitting the perforations 108 over the pin 109, 45 as shown in Fig. 4, after which the platen may be thrown back to the normal Fig. 3 position, as described above. The form which has already been written on, and which is just below the perforations 108 may 50 be torn off. In many cases, as where strong webs are used, the typist may hold the webs hooked onto the pin 109, while the platen is being thrown back into its writing position, though with some webs which are easily 55 torn it may be safer at times to merely fit the webs over the pin 109, and then allow them to spring off while the finger of the typist holds the webs against the usual smooth bar 110, to which the end gage 18 is 60 held by the usual thumb-screw 111. This bar 110 is usually grasped as a handle by the typist to throw the platen up and down, thus forming a rest for the finger of the typist in holding the webs on the pin 109. 65 Variations may be resorted to within the

scope of the invention, and portions of the improvements may be used without others.

Having thus described my invention, I claim:

1. In a front-strike typewriting machine, 70 the combination with a traveling carriage and a swing frame in said carriage, of a platen journaled in said swing frame so that when the frame is swung up a web may be drawn from the rear of the machine substantially straight beneath the platen, an extension of said frame forming a gage, and a pin on said gage adapted to have perforations in work-sheets fit over and be held thereon by the finger of the typist to align the webs. 80

2. In a front-strike typewriting machine, 85 the combination with a traveling carriage and a swing frame in said carriage, of a platen journaled in said swing frame so that when the frame is swung up a web may be drawn from the rear of the machine substantially straight beneath the platen, an extension of said frame forming a gage, an adjustable pin on said gage adapted to have perforations in work-sheets fit over and be held thereon by the finger of the typist to align the webs, and separately adjustable side gages for said webs. 90

3. In a typewriting machine, the combination with a traveling carriage and a 95 revoluble platen therein, of a carbon paper holder reciprocable upon said carriage, a spool device adapted to hold a web as a work-sheet for said platen, a clamp adapted to grasp said web, a finger-piece for causing 100 said clamp to become effective when said carbon paper holder is moved in one direction from said spool to form a bight so that the turning of the platen will draw on the bight, and means for automatically releasing said clamp when the proper bight has 105 been so formed. 110

4. In a typewriting machine, the combination with a traveling carriage, and a revoluble platen therein, of a spool turning 110 in fixed bearings adapted to deliver a web to said platen, a carbon paper holder reciprocable upon said carriage, a clamp adapted to grip said web, a finger-piece for causing said clamp to seize said web when moved in one direction, and a device for automatically releasing said clamp when the web is unwound to form a bight sufficient to permit the carriage to travel freely without twisting the web. 115

5. In a typewriting machine, the combination with a traveling carriage and a revoluble platen therein, of a spool turning on fixed bearings adapted to deliver a web to said platen, a carbon paper holder reciprocable upon said carriage, a clamp adapted to grip said web, a finger-piece for causing said clamp to seize said web when moved in one direction, a device for automatically releasing said clamp when the web is un- 120 125 130

- wound to form a bight sufficient to permit the carriage to travel freely without twisting the web, a rock shaft for operating said clamp, a rock arm splined to said shaft to 5 rock it, a bar fast to said holder to cause the splined rock arm to travel with the type-writer carriage, and a linkage extending from said carriage to said rock arm to operate said clamp.
- 10 6. In a typewriting machine, the combination with a traveling carriage and a revoluble platen therein, of a fixed spool for delivering a web to said carriage, a device 15 slideable upon said carriage, a second carriage comprising a clamp adapted to be moved for drawing on said web, means for causing said clamp to seize said web, means for automatically releasing said clamp from said web when a bight has been formed 20 therein, a table supporting said web adjacent said clamp, and a second table extending beyond said first table for supporting the bight of the web.
7. In a front-strike typewriting machine, 25 the combination with a traveling carriage, of a swing frame in said carriage, a platen journaled in said swing frame and adapted to be swung in said swing frame so that webs can be drawn from the rear substantially straight beneath the platen, a carbon paper carrier adapted to support carbon sheets between said webs, a handle for reciprocating said carbon paper carrier upon said carriage, and a pin on said swing frame 30 forming a gage over which perforations in said webs may fit to positively align the webs.
8. In a front-strike typewriting machine, 35 the combination with a traveling carriage and a revoluble platen therein, of rails forming part of said carriage, a carbon paper device running on said rails, a clamp adapted to clamp webs together, a spring normally holding said clamp ineffective, 40 and a finger-piece for making it effective.
9. In a front-strike typewriting machine, 45 the combination with a traveling carriage and a revoluble platen therein, of rails forming part of said carriage, a carbon paper device running on said rails, a clamp to clamp webs together, a spring normally holding said clamp ineffective, a finger-piece for making said clamp effective, a stop embracing one of said rails for arresting 50 said carbon paper device, a latch for holding the clamp effective when made effective by said finger-piece, and connections whereby said stop releases said latch at the arrest of said device by said stop.
- 55 10. In a front-strike typewriting machine, 55 the combination with a traveling carriage and a revoluble platen therein, of rails forming part of said carriage, a carbon paper device running on said rails, a handle 60 by which said device may be moved back- 65 ward and forward, a finger-piece connected to said handle, a clamp for grasping webs adapted to be controlled by said finger-piece, a spring normally holding said clamp ineffective, a rock-shaft on which said clamp 70 is mounted, a rock-shaft controlled by said spring, a rock-arm on said last-mentioned rock-shaft, and a cam fast on said first-mentioned rock-shaft adapted to rotate said rock-shaft to cause the clamp to be released. 75
11. In a typewriting machine, the combination with a traveling carriage and a revoluble platen therein, of means for feeding webs to said platen, a clamp adapted to grasp superposed webs together and pull 80 them off supply-rolls, and means for releasing said clamp to permit it to be drawn forwardly while the webs are being fed around said platen.
12. In a typewriting machine, the combination with a clamp, of a rock-shaft on which one jaw of said clamp is mounted, a rock-arm fast to said shaft, a second rock-shaft, a segment clamp thereon, a follower on said first rock-shaft engaging said segment clamp, a rock-arm on said second rock-shaft, a finger-piece for drawing on said last-mentioned rock-arm to rotate its shaft to make the segment effective to close the clamp, a rock-shaft comprising a spline, an 90 arm riding on said spline for operating said last-named shaft, and connections from said last-mentioned arm to said finger-piece. 95
13. In a typewriting machine, the combination with a traveling carriage, of a revoluble platen, a carbon paper device on 100 said carriage and adapted to travel therewith, said device being also adapted to be moved back and forth on said carriage, a clamp-carrying device, a connection between 105 said carbon paper device and said clamp-carrying device to move said clamp-carrying device back and forth with said carbon paper device, said connection being effective to permit movement of said carbon paper 110 device in a letter-feed direction of said platen independently of said clamp-carrying device, and means on said carbon paper device to render the clamp on said clamp-carrying device effective. 115
14. In a typewriting machine, the combination with a traveling carriage, of a revoluble platen, a carbon paper device on said carriage and adapted to travel therewith, said device being also adapted to be moved back and forth on said carriage, a clamp-carrying device, a connection between said 120 carbon paper device and said clamp-carrying device to move said clamp-carrying device back and forth with said carbon paper device, said connection being effective to permit movement of said carbon paper device in a letter-feed direction of said platen independently of said clamp-carrying device, a handle on said carbon paper device 125 130

to move the latter back and forth, and means on said carbon paper device to render the clamp on said clamp-carrying device effective, and said means comprising a finger-piece pivoted on the handle.

15. The combination with a revoluble platen, means for feeding plies of web around the platen, and means for advancing said plies to the platen, the platen being displaceable to permit the plies to be straightened out and interleaved carbons to be drawn back, of an impaling pin at the delivery side of the platen to fit perforations in the plies of web to re-register the forms printed upon each web with those printed upon the other webs.

16. The combination with a typewriting machine including a revoluble platen and feeding devices, said platen displaceable to permit straightening of plies of web carried around the platen, and also including means for retracting carbons to coöperate with fresh portions of the webs, of means connected with said carbon-retracting means to draw plies of web from a source of supply and advance them toward the typewriting machine.

17. In a typewriting machine, the combination with a carriage, of a revoluble platen thereon, means to coöperate with the platen to feed plies of web around the same, means for retracting the interleaved carbon when the plies are straightened out, a support for the plies of web to be fed into the machine, said carriage being so arranged with reference to said support that the webs advancing thereto form a reach or bight which may vibrate freely sidewise to accommodate the traveling movements of said carriage, and means for advancing the plies of web to said bight; said advancing means being operatively connected to said carbon-retracting means.

18. In a typewriting machine, the combination with a carriage, of a revoluble platen thereon, means to coöperate with the platen to feed plies of web around the same, means for retracting the interleaved carbon when the plies are straightened out, a support for the plies of web to be fed into the machine, said carriage being so arranged with reference to said support that the webs advancing thereto form a reach or bight which may vibrate freely sidewise to accommodate the traveling movements of said carriage, and means for advancing the plies of web to said bight; said advancing means being operatively connected to said carbon-retracting means to operate at the carbon-retracting operation.

19. In a typewriting machine, the combination with a carriage, of a revoluble platen thereon, means to coöperate with the platen to feed plies of web around the same, means for retracting the interleaved carbon when

the plies are straightened out, a support for the plies of web to be fed into the machine, said carriage being so arranged with reference to said support that the webs advancing thereto form a reach or bight which may vibrate freely sidewise to accommodate the traveling movements of said carriage, means for advancing the plies of web to said bight; said advancing means being operatively connected to said carbon-retracting means, and an impaling pin at the delivery side of the platen to fit re-registering holes formed in the superposed plies of web at corresponding positions on the successive forms thereon.

20. In a typewriting machine, the combination with a carriage, of a revoluble platen thereon, means to coöperate with the platen to feed plies of web around the same, said platen displaceable to permit the plies to be straightened out, a carbon-carrier for retracting the interleaved carbon, a roll support for carrying the plies of web in roll form, a clip for drawing the plies off from the rolls, said clip connected to said carbon-carrier to operate during the retraction of the carbons, and means for releasing the clip to permit the clip to be returned to position to take a fresh grip upon the plies.

21. In a typewriting machine, the combination with a carriage, of a revoluble platen thereon, means to coöperate with the platen to feed plies of web around the same, said platen displaceable to permit the plies to be straightened out, a carbon-carrier for retracting the interleaved carbon, a roll support for carrying the plies of web in roll form, a clip for drawing the plies off from the rolls, said clip connected to said carbon-carrier to operate during the retraction of the carbons, means for releasing the clip to permit the clip to be returned to position to take a fresh grip upon the plies, and means to detain the clip in gripping position.

22. In a typewriting machine, the combination with a carriage, of a revoluble platen thereon, means to coöperate with the platen to feed plies of web around the same, said platen displaceable to permit the plies to be straightened out, a carbon-carrier for retracting the interleaved carbon, a roll support for carrying the plies of web in roll form, a clip for drawing the plies off from the rolls, said clip connected to said carbon-carrier to operate during the retraction of the carbons, means for releasing the clip to permit the clip to be returned to position to take a fresh grip upon the plies, said roll support being fixed, and a traveling connection being provided between said carbon-carrier and said clip to accommodate the travel of the typewriter carriage.

23. In a typewriting machine, the combination with a carriage, of a revoluble platen thereon, means to coöperate with the

platen to feed plies of web around the same, said platen displaceable to permit the plies to be straightened out, a carbon-carrier for retracting the interleaved carbon, a roll support for carrying the plies of web in roll form, a clip for drawing the plies off from the rolls, said clip connected to said carbon-carrier to operate during the retraction of the carbons, means for releasing the clip to permit the clip to be returned to position to take a fresh grip upon the plies, said roll support being near the front of the machine, and a table in rear of the rolls, over which the plies run, the rear end of said table being below the introductory side of the typewriting machine, to permit a bight or reach of web to hang and vibrate freely edgewise, to accommodate the travel of the typewriter carriage.

20 24. In a typewriting machine, the combination with a carriage having a platen, of a carbon-carrier movable on said carriage, a clamp for advancing the plies of web toward the typewriting machine, said clamp operatively connected to said carbon-carrier, a finger-piece upon said carbon-carrier, means to enable said finger-piece to close said clamp, a latch for holding said clamp closed, and a stop for engaging said latch at the movement of said carbon-carrier and causing said clamp to open.

25 25. In a typewriting machine, the combination with a carriage having a platen, of a carbon-carrier movable on said carriage, a clamp for advancing the plies of web toward the typewriting machine, said clamp operatively connected to said carbon-carrier, a finger-piece upon said carbon-carrier, means to enable said finger-piece to close said clamp, a latch for holding said clamp closed, a stop for engaging said latch at the movement of said carbon-carrier and causing said clamp to open said carbon-carrier being arrested by said stop, and connections between said carbon-carrier and said clamp to accommodate the travel of the typewriter carriage in letter-feeding direction.

26. The combination with a traveling carriage and a revoluble platen thereon, of rails forming part of said carriage, a carbon-carrier running upon said rails, a clamping device arranged at a distance from said carriage to permit a bight of webs on the introductory side of said carriage, and means for connecting said clamp to said carbon-carrier to advance the webs toward the carriage when the carbons are being retracted.

27. In a typewriting machine, the combination with a traveling carriage, a revoluble platen carried thereby, and a line-spacing mechanism for said platen, of means for conducting a web to said platen, a member mounted for advance and return movements and arranged to advance at the line-feeding movements of the platen, and means connected to said member for unwinding a supply of web from a spool preparatory to the typing of a fresh form upon the web.

28. In a typewriting machine, the combination of a traveling carriage, a revoluble line-spacing platen carried thereby, means for conducting a web to said platen, a carbon-carrier having advance and return movements, and means connected to said carbon-carrier and including a web-clamp for pulling a supply of web from a spool preparatory to the typing of a fresh form upon the web.

29. In a typewriting machine, the combination with a traveling carriage, a revoluble line-spacing platen carried thereby, means for conducting a web to said platen, a carbon-carrier having advance and return movements, and means connected to said carbon-carrier and effective upon the return stroke of said carbon-carrier, for unwinding a supply of web from a spool preparatory to the typing of a fresh form upon the web.
